UNITED STATES PATENT OFFICE.

HERMAN G. KOTTEN, OF NEW YORK, N. Y.

PNEUMATIC TOOL.

SPECIFICATION forming part of Letters Patent No. 739,609, dated September 22, 1903.

Application filed June 8, 1903. Serial No. 160,533. (No model.)

To all whom it may concern:

Be it known that I, HERMAN G. KOTTEN, a citizen of the United States, residing at New York, in the county of New York and State of New York, have invented a new and useful Improvement in Pneumatic Tools, of which the following is a specification.

My invention relates to pneumatic tools; and it consists of a novel construction of a push-handle for the same, whereby the reciprocations of the hammering-piston are automatically stopped without requiring any attention from the operator as soon as the pressure of the tool upon the work is relieved. It has heretofore been proposed to supply pneumatic tools of various types with grasping-handles and to provide these handles with various types of manually-operated levers or throttle-valve devices, and it has also been heretofore attempted to construct push-handles adapted to coact with throttle-valves operated by coil-springs and the like. In my present invention, however, I dispense entirely with the use of springs and provide a device which is automatic under all conditions and requires no attention whatever from the operator, the number of parts and the expense of manufacture are reduced to a minimum, and the liability of damage to any of the parts is entirely obviated.

To the above ends my invention consists, broadly, of the novel combination of a pneumatic tool, a cylinder cap or head therefor, a differential throttle-valve mounted in said cap, and a handle adapted to coact with said throttle-valve; the arrangement of the parts being such that upon the removal of the tool from the work or the release of the pressure upon the handle the live-air pressure upon the differential area of the throttle-valve automatically closes the same and effects the stoppage of the tool.

It further consists of other novel features of construction, all as will be hereinafter fully set forth.

Figure 1 represents a longitudinal sectional view of a pneumatic tool having a push-handle, automatic throttle-valve, and its adjuncts embodying my invention. Fig. 2 represents a side elevation of Fig. 1. Fig. 3 represents a section on line xx , Fig. 2. Fig. 4 represents, on a reduced scale, a detail view

of Fig. 1, showing the position the throttle-valve automatically assumes with respect to the inlet-port or pressure-supply duct when the tool is removed from the work.

Similar numerals of reference indicate corresponding parts in the figures.

Referring to the drawings, 1 designates the cylinder of a pneumatic tool, having the hammering-piston 2 therein, said cylinder being engaged by the cylinder head or cap 3, which is adapted to be in threaded or other engagement therewith and is held in the desired position by means of the threaded bolt or other fastening device 4. In the body portion 5 of the cylinder-cap 3 is located the inlet-port or pressure-supply duct 6, into which compressed air is led through the coupling air-strainer 7, which is of the usual construction and is adapted to have the extremity of the compressed-air inlet pipe or hose (not shown) connected thereto in the usual manner. It will be understood that the coupling-strainer 7 is constructed in the conventional manner and is provided with wire-gauze, through which the motive fluid is strained before reaching the working parts of the tool. I have deemed it unnecessary to show this gauze and to describe the precise construction in detail, since the same will be familiar to those skilled in this art. From the inlet port or passage 6 leads the passage 8 into the chamber 9 of the hollow differential distribution-valve 10 contained in the valve-box 10^X, it being understood that when the parts are in the position seen in Fig. 1 the compressed air passes through the passage 9 and ports 11 into the piston-chamber 12 and drives the piston 2 downwardly from the position seen in Fig. 1 against the chisel or other cutting tool. (Not shown.)

When the piston 2 moves from the position seen in Fig. 1, it will be understood that the exhaust takes place through the passage and port 13 into the passage 14, (shown dotted in Fig. 1,) into the annular chamber 15, and out the port 16 in the cylinder-cap and the port 17 in the sleeve 18 of the handle 19 to the atmosphere, it being also understood that at the proper intervals live-air pressure enters the passage 20 and flows through the passage 21 upon the larger or differential area 22 of the valve 10.

The pneumatic tool to which my invention is particularly adapted and which I have shown herein is the well-known type of tool called the "Keller" tool, and the detailed operation of the valve and its piston will be understood from patent to Julius Keller, No. 647,415, granted April 10, 1900, a portion of the tool therein being shown herein in Fig. 1; but I have deemed it unnecessary to show and described in detail the entire Keller tool, since it will be understood that the salient features of my present invention may be employed with other pneumatic tools with equal efficiency, and I have shown my invention applied to that form of tool which I consider most efficient in practice.

23 designates the automatic throttle-valve employed, the same consisting of the head 24, having the large differential area 25, and 20 a smaller head 26, having a small differential area 32, said areas 25 and 32 being juxtaposed to each other, said heads being connected by the neck 27.

28 designates a washer, of leather or other 25 resilient or cushioning material, which is interposed between the cylinder-cap 3 and the contiguous wall 29 of the handle 19.

30 designates a slot in the sleeve or extension 18 of the handle 19, the upper and lower 30 extremities of which are adapted to contact with the head 31 of the coupling or strainer 7, whereby the movement of the handle 19 with respect to the cylinder-cap is limited, as will be evident.

35 The operation is as follows: The parts normally appear as seen in Fig. 4. Assuming live-air pressure to be entering the pressure-supply passage or port 6, it will be apparent that the flow of the same will be as already described when the parts are in the position seen in Fig. 1, which position they assume when the operator grasps the handle 19 and presses the tool against the work, the valve 23 assuming the position seen in Fig. 1, with 45 its neck extending across the passage 6, and the exhaust-ports 16 and 17 being in alinement. The parts being in this position, the operation of the tool, or, in other words, the reciprocation of the piston, will occur without 50 attention upon the part of the operator. As soon as the pressure is removed from the handle 19 or the tool is removed from its work it will be apparent that the live-air pressure upon the large area 25 and upon 55 the lower end of the piston 28 will cause the differential throttle-valve 23 to move in the direction indicated by the arrow *a*, whereupon the parts will appear in the position seen in Fig. 4, and the head 26 being now in 60 the position seen will prevent the flow of compressed air to the port 8, and the reciprocation of the piston will cease. At the same time the exhaust-port 17 will pass out of alinement with the port 16, as will also be 65 seen in Fig. 4. The contact of the walls of the slot 30 with the portion 31 of the strainer 7 will act as a stop for the handle and will

prevent improper movement of the throttle-valve 23, handle 19, and their adjuncts.

It will be apparent that changes may be 70 made in the manner of constructing and assembling the various parts as regards the form, operation, size, and minor details thereof without departing from the spirit of my invention, and I therefore reserve to myself 75 the right to make all such changes and do not desire to be limited in every instance to the exact construction I have herein shown and described.

Having thus described my invention, what 80 I claim as new, and desire to secure by Letters Patent, is—

1. In a device of the character described, a cylinder - head, a throttle - valve mounted therein and having differential pressure areas 85 juxtaposed to each other, a handle movably supported upon said head and means for causing said valve and handle to move outwardly by the action of compressed air upon the larger pressure area of said valve, when 90 pressure upon said handle is removed.

2. In a device of the character described, a cylinder-head, a throttle-valve therein, having heads of different sizes joined by a neck, differential pressure areas on said heads on 95 opposite ends of said neck between which the motive fluid passes to the working parts of the tool, a handle movably mounted upon said head, means for limiting the movement of said handle and means for permitting pressure upon said handle to open said valve.

3. In a device of the character described, a cylinder-head, having a pressure-supply duct extending therethrough, a throttle-valve consisting of a plurality of heads, having differential pressure areas joined by a neck, said neck being in alinement with said pressure-supply duct, when live air is being admitted to the working parts of the tool, and exhaust-ports in an extension of said handle and in 110 said head, said ports being adapted to aline with each other when the throttle-valve is open and said ports being out of alinement when the throttle - valve is automatically closed.

4. The combination of a tool-cylinder, a cylinder-head therefor, a valve-box, a distribution-valve contained in said box, means for securing said head to said cylinder, a throttle-valve in said head, moving in alinement with said distribution-valve, said throttle-valve consisting of a plurality of heads joined by a neck, the opposing surfaces of said heads having differential areas, a handle having an extension movably mounted upon said head, means for limiting the movement of said extension, and a washer located between said head and handle.

5. The combination of a grasping-handle having a slot therein, a cylinder-cap upon 130 which said handle is movably supported, a pressure-supply duct in said cap, a device communicating with said pressure - supply duct and adapted to enter said slot and limit

the movement of said handle, a washer located between said handle and cap, and a differential throttle-valve, located in said pressure-supply duct, said throttle-valve consisting of heads of different diameters joined by a neck, whereby live-air pressure acting upon the large differential area closes said pressure-supply duct and the pressure of the handle upon the larger of said heads when the tool is applied to the head, opens said supply-duct.

6. In a device of the character specified, a cylinder-head, a grasping-handle longitudinally movable thereon and separate means operated by the movement of said handle for simultaneously opening and closing the inlet and exhaust ports of said device.

7. In a device of the character specified, a cylinder-head, an aperture extending longitudinally through said head, a throttle-valve in said aperture, having differential pressure areas juxtaposed to each other, an inlet air-passage controlled by said valve, a grasping-handle movable on said cylinder-head and adapted to open said valve and means op-

erated by fluid-pressure for closing said valve.

8. In a device of the character specified, a cylinder-head, an inlet air-passage in said head, a throttle-valve having heads of different diameters and a reduced neck therebetween, and a grasping-handle movable on said cylinder-head and operative to shift said valve so that its neck portion is interposed in said inlet-passage, said piston-heads being operative by means of the air entering said inlet-passage to actuate one of said heads to cut off the flow of air therethrough.

9. In a device of the character specified, a cylinder-head, a throttle-valve movable therein, and a handle manually movable on said head and operative to open said valve, said valve having an enlarged differential pressure area, whereby it closes and retracts said handle when manual pressure is removed therefrom.

HERMAN G. KOTTER.
